Ivan E. A. Kornigberg

UNITED STATES PATENT OFFICE.

GUSTAV ADOLF MÄUSERT, OF BROOKLYN, NEW YORK.

SHOE-POLISHING DEVICE.

1,232,065.

Specification of Letters Patent.

Patented July 3, 1917.

Application filed June 15, 1916. Serial No. 103,874.

To all whom it may concern:

Be it known that I, GUSTAV ADOLF MÄUSERT, citizen of the German Empire, and a resident of Brooklyn, in the county of 5 Kings and State of New York, have invented certain new and useful Improvements in Shoe-Polishing Devices, of which the following is a specification.

This invention relates to improvements in 10 shoe polishing devices and the object of the invention is to provide a shoe polishing tool or device adapted especially for individual use and so arranged and constructed that it may be effectively used on one's own shoes 15 and readily carried about as for instance when traveling.

One object of the invention is to provide a shoe polishing device adapted to be manufactured at a very low figure so as to be 20 sold very cheaply, yet so designed that a strong and reliable device is obtained.

Another object is to arrange the device so that the polishing cloth may be readily detached and renewed.

25 Other objects will appear as this specification proceeds while reference is had to the accompanying drawings illustrating the preferred form of my invention together with several modifications and in which—

30 Figure 1 is a view showing the use of the invention.

Fig. 2 is a view of one form of the shoe polishing device embodying the invention.

Fig. 3 shows the polishing cloth used with 35 the device illustrated in Fig. 2.

Referring to the drawing the shoe polishing device comprises a cloth 10 at each end of which is a handle 11. As shown, the handle is made of wood and preferably 40 tapered to form a suitable grip portion 12 and to provide the necessary strength at the same time. The lower end 13 is wedge shaped for the attachment of the cloth which may be of any suitable fabric woven, 45 folded or otherwise formed as shown in Fig. 3 in which the cloth is shown as shaped with open ends 14, closed circumferentially and of less diameter than the width of the wedge 13 of the handle and provided with an opening 15 intermediate the ends.

With a cloth constructed as described, the handles are attached by being passed

through the side opening 15 and then pulled out endwise through the openings 14 into the position shown in Fig. 2 where it will be 55 seen that the handles are firmly wedged in the ends of the cloth and that during the use of the device, the pull upon the handles only serves to still further wedge them in the cloth so the latter can not become detached accidentally. The cloth may be shaped by folding and sewing as indicated at 16, or may be shaped in any other suitable manner.

If desired the cloth may be secured to the 65 handle by means of a clamp 19 in the form of a band, preferably of metal which firmly clamps the cloth to the handle by sliding the clamp downward until the cloth and handle are firmly wedged together as will be under- 70 stood.

The band 19 may be provided with prongs 20 which bite into the cloth and handle as the clamp is pushed toward the wider wedge end 13 of the handle.

It will be noted that in the construction described in the foregoing, the cloth is detachably secured to the handles by having the latter wedged inside the cloth as in Fig. 2, and in addition clamping means may be 80 used as shown. Thus the use of nails or tacks is avoided and a simpler and cheaper method of construction provided in which the cloth is securely attached, yet quickly detached and renewed.

As shown in Fig. 1 the device may be used by a person without the latter having to bend, which is objectionable in many cases as for instance when the user is stout. It may of course also be used comfortably 90 while the person is sitting.

Various changes in the form and construction of the details of my invention may be made without departing from the principle thereof as defined by the scope of the 95 appended claims.

I claim:

1. A shoe polishing device comprising a cloth consisting of at least two thicknesses of material sewed together lengthwise and 100 narrowed at the ends, a handle, members projecting from said handle and adapted to pass inside and wedge in said ends of the cloth and clamping means coöoperating with the said

members for securing the cloth to the said handles.

2. A shoe polishing device comprising a cloth having tubular ends, a handle for each end of the cloth adapted to be inserted within said tubular ends, said handles having wedge shaped ends whereby to wedge the

handles inside the ends of the cloth and clamping means surrounding said handles and cloth for clamping the same together. 10

Signed at New York in the county of New York and State of New York this 13th day of June A. D. 1916.

GUSTAV ADOLF MÄUSERT.

Copies of this patent may be obtained for five cents each, by addressing the "Commissioner of Patents, Washington, D. C."
